GAME APPARATUS

Clifford V. Brown, Pittsburgh, Pa.

Application January 20, 1934, Serial No. 707,589

6 Claims. (Cl. 273—146)

This invention relates to an improved game apparatus and more particularly to an improved die adapted to be used in playing various games.

An object of the invention is to provide an improved die or block having a relatively large number of character-bearing faces so arranged that the chances are equal for each of the faces to turn uppermost when the die is rolled, and an exceedingly wide range of play is afforded.

10 A particularly important novel characteristic of the invention resides in the special form of die having a large number of faces with certain of the faces differing in shape and of less area than other faces thereof but so positioned and with the plane angles thereof relatively to the plane angles of the larger faces that the smaller faces are as likely to turn up as the larger faces when the die is rolled.

20 Another object of the invention is to provide an improved die or block having a relatively large number of character bearing faces, and which will be of a construction that will be satisfactory in use and can be easily produced.

25 The invention, with other objects and advantages thereof, and the particular construction, combination, and arrangement of parts comprising the same, will be understood from the hereinafter contained detail description when considered in connection with the accompanying drawing forming part hereof and illustrating one embodiment of the invention.

In the drawing:

Figure 1 is an elevation of a die constructed in accordance with the present invention;

35 Figure 2 is a plan view;

Figure 3 is a vertical section on the line 3—3 of Figure 1;

40 Figures 4 and 5 are detail views of the two sections of the die; and

Figure 6 is a developed view showing the characters upon all of the faces of the die.

45 While a preferred embodiment of the invention is illustrated in the drawing, it will of course be understood that changes and modifications may be made in the particular construction shown, and the invention may be embodied in other forms, as will appeal to those skilled in the art and falling within the scope of the appended claims, without departing from the spirit of the invention.

50 The particular construction of die or block illustrated in the drawing comprises a polyhedron of general spherical form having thirty-two faces arranged in four annular series *a*, *b*, *c*, *d*, two of the series of faces being disposed at each side of a plane *e*—*e* bisecting the polyhedron, and each of the faces at one side of this central plane being disposed parallel with one of the faces at the opposite side thereof. The intermediate series of faces *b*, *c*, extend oblique-

ly from the central plane *e*—*e* of the polyhedron. These are trapezoidal in shape and of similar size. The end series of faces *a*, *d*, extend obliquely from the series of intermediate faces. Each of the end faces is an isosceles triangle. The end faces are similar in size to each other and of less area than the intermediate series of faces. It will be noted that the plane angles of the end faces *a*, *d*, with the central plane *e*—*e*, and the plane angles of the intermediate faces *b*, *d*, with a line perpendicular to the plane *e*—*e* are different, the dihedral angle between the two intermediate series of faces being greater than the dihedral angle between each of the intermediate series of faces and the adjacent outer series of faces.

5 10 15 It will also be noted that although the triangular-shaped end faces *a*, *d*, are smaller than the intermediate faces *b*, *c*, said end faces due to the difference referred to in the plane angles of the respective faces are as likely to turn uppermost as are the larger intermediate faces, when the die is thrown. In the particular construction shown, the plane angles of the faces *a*, *d*, with the plane *e*—*e* are 21° 30', and the plane angles of the faces *b*, *c*, with a line perpendicular to the plane *e*—*e* are 20° 30'.

20 25 30 35 In the particular construction shown in the drawing, the faces of the die or block bear the numbers one to thirty-two. As shown in Figure 6, the relative arrangement of the numbers on the several faces is such that the sum of the numbers on the outer series of faces *a*, *d*, is the same as the sum of the numbers on the two intermediate series of faces *b*, *c*, this arrangement insuring an equal chance of rolling a high or low number.

40 45 The die or block is provided with ribs 1 extending parallel with the plane *e*—*e*, and with a plurality of converging ribs 2, said ribs providing raised wall portions bordering the character-bearing faces of the die and serving to prevent rocking of the die when the same is thrown or rolled.

50 55 60 The die or block is made up of two hollow substantially hemispherical sections 3, 4, molded from glass, "bakelite", or any other suitable material. The sections at their marginal portions have interfitting portions and are secured together at their abutting marginal portions by a suitable cement. The interfitting portions referred to comprise an annular flange 5 on the section 3 fitting into an annular groove 6 in the section 4, and a lug 7 on the section 4 engaging a recess 8 in the flange 5 of the section 3. The lug 7 and recess 8 serve to facilitate quick and accurate assembly of the sections. The characters on the faces of the die or block, which characters are formed by molding, are shown raised; and the embossed characters are prefer-

ably given a color contrasting to that of the faces.

The invention comprehends the use of two dice or blocks of the construction hereinbefore set forth in playing several different forms of games. One game employing the specific characters shown on the faces of the die or block is the following: In connection with the two dice or blocks, a chart is provided having thirty-two columns of figures with thirty-two numbers to the column, the columns and the transverse lines of numbers of the columns being both numbered consecutively.

The two dice or blocks are identical except that they bear some distinguishing characteristic, as by having the numbers thereon of contrasting color. The numbers of one of the dice or blocks relate to the columns, and the numbers of the other die or block relate to the transverse lines of figures on the chart. When the dice are thrown, the number that appears on the chart at the intersection of the line and column indicated by the dice is the number for the play.

The game is played by the players taking turns at rolling the dice until the sum of the numbers rolled by one of the players reaches a predetermined number, the player first reaching this number winning the game.

What I claim is:

1. A game device comprising a polyhedron of general spherical form having an intermediate annular series of trapezoidal character-bearing faces of similar size at each side of and extending obliquely from a central plane of the polyhedron, and two outer annular series of character-bearing faces similar in size and shape to each other, each series extending obliquely from one of the intermediate series of faces, the two outer series of faces being of less size than the intermediate series of faces, and the dihedral angle between the two intermediate annular series of faces being greater than the dihedral angle between each of the intermediate series of faces and the adjacent outer series of faces, whereby the chances are equalized for the outer series of smaller faces and the intermediate series of larger faces to appear uppermost when the device is rolled, each of the faces bearing a character relating to the game.

2. A game device comprising a polyhedron of general spherical form having an intermediate annular series of trapezoidal character-bearing faces of similar size at each side of and extending obliquely from a central plane of the polyhedron, and two outer annular series of character-bearing faces similar in size and shape to each other, each series extending obliquely from one of the intermediate series of faces, the two outer series of faces being of less size than the intermediate series of faces, and said polyhedron being composed of two hollow substantially hemispherical sections, the marginal portion of one of said sections being provided with an annular groove and the marginal portion of the other section having an annular flange to fit in said groove, and means for assembling the sections in a definite predetermined relation including a recess in a marginal portion of one of the sections and a lug on the marginal portion of the other section to engage said recess, said sections being secured together by an adhesive.

3. A game device comprising a polyhedron of general spherical form having an intermediate annular series of trapezoidal character-bearing faces of similar size at each side of and extending obliquely from a central plane of the polyhedron,

and two outer annular series of character-bearing faces similar in size and shape to each other, each series extending obliquely from one of the intermediate series of faces, the two outer series of faces being of less size than the intermediate series of faces, and said polyhedron being composed of two substantially hemispherical sections, means for assembling the sections in a definite predetermined relation including a recess in a marginal portion of one of the sections and a lug on the marginal portion of the other section to engage said recess, and means for securing the sections together.

4. A game device comprising a polyhedron of general spherical form having an intermediate annular series of trapezoidal faces of similar size at each side of and extending obliquely from a central plane of the polyhedron, and two annular series of end faces, each series extending obliquely from one of the series of intermediate faces, said end faces each being an isosceles triangle and similar in size to each other and smaller than the first-mentioned faces, the dihedral angle between the two intermediate annular series of faces being greater than the dihedral angle between each of the intermediate series of faces and the adjacent outer series of faces, whereby the chances are equalized for the outer series of smaller faces and the intermediate series of larger faces to appear uppermost when the device is rolled, each of the faces bearing a character relating to the game.

5. A game device comprising a polyhedron of general spherical form having an intermediate annular series of character-bearing faces of similar shape and size at each side of and extending obliquely from a central plane of the polyhedron, and two outer annular series of character-bearing faces similar in size and shape to each other, each series extending obliquely from one of the intermediate series of faces, the two outer series of faces being of less size than the intermediate series of faces, the axis of the polyhedron perpendicular to said central plane being shorter than its other axis and the angles of the outer series of faces with said central plane being greater than the angles of the intermediate series of faces with a line perpendicular to said central plane, whereby the chances are equalized for the outer series of smaller faces and the intermediate series of larger faces to appear uppermost when the device is rolled.

6. A game device comprising a polyhedron of general spherical form having an intermediate annular series of faces of similar shape and size at each side of and extending obliquely from a central plane thereof, and two outer annular series of faces similar in size and shape to each other, each series extending obliquely from one of the intermediate series of faces, the two outer series of faces being of less size than the intermediate series of faces, and the dihedral angle between the two intermediate series of faces being greater than the dihedral angle between each of the intermediate series of faces and the adjacent outer series of faces, whereby the chances are equalized for the outer series of smaller faces and the intermediate series of larger faces to appear uppermost when the device is rolled, each of said faces bearing a number, the numbers being arranged on the several faces so that the sum of the numbers on the two outer series of faces is the same as the sum of the numbers on the two intermediate series of faces.
